[57] CLAIM

The ornamental design for a connection board for use in vehicles, as shown and described.

DESCRIPTION

FIG. 1 is a top plan view of a connector board for use in vehicles showing our new design;

FIG. 2 is a front elevational view thereof;

FIG. 3 is a bottom plan view thereof;

FIG. 4 is a left side elevational view thereof;

FIG. 5 is a right side elevational view thereof;

FIG. 6 is a rear elevational view thereof;

FIG. 7 is a front and upper left perspective view of a connector board for use in vehicles showing our new design on a reduced scale with the cover in the open position;

FIG. 8 is a front and upper right perspective view of a connector board for use in vehicles showing our new design; and

FIG. 9 is a rear and lower left perspective view thereof.

FIG. 1

FIG. 2
